UNITED STATES PATENT OFFICE

THEODOR PATERMANN, OF RATIBOR, GERMANY

ELECTRIC HAIR DRIER

Application filed November 7, 1929, Serial No. 405,473, and in Germany August 6, 1929.

This invention relates to an electric hair-drying device and consists in the provision of a metallic hair net adapted to be secured by means of an elastic band to the human head 5 and to support a domed electric heating element so as to receive heat from the latter, the heating element being fitted with a cover which holds the electric leads.

Fig. 1 of the accompanying drawings represents a front view of the net,

Fig. 2 is a top view of the same,

Fig. 3 is a sectional front view of the entire device,

Fig. 4 is a top view of the device,

Fig. 5 is a view of the fastening elements according to one construction,

Fig. 6 is a cross-section of part of the fastening elements,

Fig. 7 is a view of a modified form of the fastening element, and

Fig. 8 is a cross-section of the latter.

The hair-drying device comprises a metallic hair net *d* preferably made of copper strips or wire and adapted to fit the crown 25 of the human head. The net is connected at the front to a soft, semi-circular rim *a* adapted to bear against the forehead, and eyelets *b* are made at the ends of the rim for the reception of elastic straps *c* adapted to be connected at the back of the head for securing the drying net in position. The rim *a* is either formed with a groove, as shown in Fig. 6, or with a recess, as shown in Fig. 8, for the reception of the edge of the net which 35 may be fastened to the rim by means of rivets.

For heating the net while applied to the head, a domed electric heating element is provided which is adapted to cover the net.

40 In order to maintain the heating element at a safe distance from the head and enable the vapours to escape, the net is provided with a plurality of spacing ribs *e* placed on its top surface.

45 The heating element is mounted in the wide end of a funnel-shaped cover *g* the narrow end of which is provided with a socket for connection by means of a plug *i* to the electric source.

50 Apertures may be made in the heating ele-

ment and in the cover *g* for the discharge of vapours.

The heating of the moist hair on the head will have a refreshing effect, and the hair, after being dried in this fashion and combed, 55 will have a pleasing appearance.

I claim:—

1. An electric hair-drier comprising a metallic hair net, an elastic band for connecting said net to the human head, a domed 60 electric heating element adapted to cover said net so as to supply heat thereto, and a cover for said heating element.

2. A hair-drier as claimed in claim 1 in combination with ribs applied to the net as 65 spacing elements between it and the heating element.

3. An electric hair-drier comprising a metallic hair net, a semi-circular rim of soft material to which said net is connected, elastic bands connected to the rim for securing the net to the human head, a domed electric heating element adapted to cover said net and supply heat thereto, ribs arranged on the net as spacing elements between it and the heating element, a funnel-shaped cover holding said heating element in its wide end, and means for plugging electric leads for the heating element into the narrow end of said cover.

THEODOR PATERMANN.
